Primary Examiner — Kendra Leslie Hamilton(74) *Attorney, Agent, or Firm* — Murray, Ziel & Johnston; Aaron Powell(57) **CLAIM**

The ornamental design for a teether toy, as shown and described.

DESCRIPTION

FIG. 1 is a top, front, right side perspective view of a teether toy, showing my new design;

FIG. 2 is a bottom, rear, left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The evenly dashed broken lines illustrate portions of the teether toy and form no part of the claimed design.

1 Claim, 8 Drawing Sheets(56)
